UNITED STATES PATENT OFFICE.

OZRO S. FELLOWS, OF BEDFORD, ASSIGNOR OF ONE-HALF TO DAVID COY,
OF BATTLE CREEK, MICHIGAN.

BAND-CUTTER AND FEEDER FOR THRASHING-MACHINES.

SPECIFICATION forming part of Letters Patent No. 467,464, dated January 19, 1892.

Application filed August 6, 1886. Serial No. 210,236. (No model.)

To all whom it may concern:

Be it known that I, OZRO S. FELLOWS, a citizen of the United States, and a resident of Bedford, in the county of Calhoun and State 5 of Michigan, have invented certain new and useful Improvements in Band-Cutters and Feeders for Thrashing-Machines, of which the following is so full, clear, and exact a description as will enable others skilled in the art to 10 to which my invention appertains to make and use the same.

This invention relates to band-cutters and feeders for thrashing-machines; and it consists in certain peculiarities in the construction, arrangement, and combinations of the 15 various parts thereof, substantially as hereinafter described, and particularly pointed out in the subjoined claims.

The object of my invention is to furnish a 20 simple and effective attachment to thrashing-machines, which will quickly convey the bound bundles of grain from any adjacent point on the mow, stack, or load to the thrasher and sever the bands of said bundles in their 25 passage to the thrashing-machine.

In the accompanying drawings, illustrating 30 my invention, Figure 1 is a perspective view of my improved feeder and band-cutter. Fig. 2 is a longitudinal sectional view of the same, showing the interior construction thereof. Fig. 3 is a partial front end view of the same and shows the means for operating the endless carrier. Fig. 4 is a detail view of a folding platform onto which the grain is fed 35 when the bands serving to retain the same in bundles have been severed. Fig. 5 is a perspective of my improved band-cutter and feeder attached to a thrashing-machine, and shows the means of such attachment and also 40 mechanism for starting and stopping the operation of the cutter and feeder without interfering with the operation of the thrasher. Fig. 6 is an end view showing the folding platform attached at one end to the carrier- 45 box and at its opposite end to the thrashing-machine. Fig. 7 is an enlarged view of one of the bundle-carrier forks detached.

The same letters and figures of reference 50 are used to designate the same parts in the several figures.

m designates the frame of my improved

band-cutter and feeder, which frame is open at its bottom and provided with transverse bracing-bars *n*, situated suitable distances apart along its length and commencing from 55 points near its opposite extremities. As a means for further strengthening this frame *m*, I have adopted a truss-rod *D*, located near one side thereof and having its opposite end secured to those bracing-bars *n*, 60 which are located nearest the ends of the frame, while its central or lowermost portion is suitably sprung over and secured to a projection *d*, depending from the central bracing-bar *n*, all of which is clearly shown in Fig. 65 2. It has been found from practical experience that such a truss gives the requisite amount of strength to the device and at the same time adds very little to its weight. For this reason I prefer it to any other known 70 means of bracing; but I do not wish to be understood as limiting myself to its use. At the ends of this frame *m* are located sprocket-wheels *C C'*, which are fixed on horizontal shafts having their bearings in the sides of 75 said frame. These sprocket-wheels receive their motion from any suitable motive power through the intermediate gearing hereinafter described, and they operate the endless carrier *B*, which is provided with forks *E*, hereinafter described. They are made sufficiently 80 large to project down into a trough *F*, which is attached by any suitable means to the frame *m*, and up through the top of said frame into a carrier-box *A*, and it therefore follows 85 that the endless carrier *B*, above referred to, occupies a portion of the space along the bottom of the box *A* and a portion of the interior of the trough *F*. This trough *F* is open at its top, is longer but narrower than the 90 frame *m*, and projects slightly beyond the delivery end 2 of the same and is designed to catch any of the grain which may be carried along by the forks *E* after the bands of the bundles have been severed. To prevent liability 95 of the straw falling into said trough through the opening in the top of the front end 1 of the device I provide a guard *G*, which for the sake of lightness may be constructed in the form of a fork having its prongs *g* projecting 100 over said opening. This guard is pivotally secured at its outer edge to permit it to be

readily raised, in order to give access to the trough F at this point, when it is desired to clean the same.

At suitable distances apart along the length 5 of the chair B are hinged the bundle-carrier forks E above referred to, one of which is shown in detail in Fig. 7. Each of these forks is made of wire or other suitable metal, and from one of its prongs e said wire projects 10 forwardly a suitable distance and rearwardly to the place of commencement, (forming the projection e'), from which point it is bent at a right angle and passes through a loop b on the carrier-chain and thence upward to form 15 the other prong. The forwardly-projecting portions e' of these forks E are made heavy enough to overbalance said forks, so that when the latter reach the delivery end 2 of the device, at which time the bands of the 20 bundles they carry will be severed, the weight of such ends of the forks will cause said prongs to drop and swing downward parallel with and prone on the chair, which movement of the prongs is assisted and rendered positive 25 by the fact that their prongs e will strike the end of the trough F and ride down the inclined plane formed by curving this end of said trough inward and downward, as shown. The forks thus automatically release themselves 30 from the unbound grain, which falls onto a platform N, hereinafter described, and is pushed along the same by the movement of the grain, which is being rapidly delivered at this point to the thrashing-machine. The 35 forks, when released from the unbound grain, pass forwardly through the trough F to the front end of the same, at which point their portions e' engage and ride up an inclined plane, formed by a curved strip P, which is 40 located beside the sprocket-wheel C' and projects into the opening p, which automatically returns said prongs to a vertical position and forcibly thrusts them into the bundles fed to the carrier. The prongs of the forks E are 45 rigidly held in an upright position while passing through the box A and thereby prevented from releasing themselves from the bundles of grain before the bands of the same have been severed and the unbound grain delivered 50 at the end of the carrier by means of lugs or ears o, which extend laterally from the carrier-chain and prevent upward movement of the weighted ends e' of the forks E, it being 55 of course understood that downward movement of said ends of the forks will be prevented by the bottom of the box A.

L designates the band-severing knife, which is secured to the bottom of the box A in the path of the bundles. This knife is preferably made substantially of the form shown, and its upper outer edge or point l is the cutting-surface. In order that the band will be brought positively into contact with the cutting-edge of this knife, I have provided a triangular piece M and a toothed wheel K. This triangular piece M is located beneath the cutting-point of the knife L, and said

toothed wheel is so located that its teeth will project up through a slot formed in the bottom of the box A, immediately to the rear of 70 and in line with said triangular piece. When the bundle of grain reaches this triangular piece M, it rides up the surface thereof and is grasped by the teeth of the wheel K and fed by said wheel to the band-severing knife, 75 reaching the same in an inclined position, whereby the entrance beneath the band of the cutting-point of the knife is facilitated, when further rearward motion of the bundles causes severance of said bands, as is ob- 80 vious.

The carrier-box A is formed by the two leaves a a and the top of the frame m of my device. These leaves a a are each semi-cylindrical in shape and are hinged a suitable 85 distance apart to the top of said frame, so that they can be folded together when the device is not in use, and when so folded they will form a cylinder, rendering the device very compact, which is a matter of prime 90 importance in transportation, and at the same time protecting the feeding and severing devices from the ruinous influence of the weather.

A means for operating the serrated or 95 toothed wheel K and the sprocket-wheels C C', and through them the bundle-feeding devices, will now be described.

Q designates a frame comprising the uprights q q' and the horizontal and inclined 100 strips q³ and q², respectively. The uprights q q' are pivotally secured together preferably by means of the hooks 5 and chain 6 shown, so as to permit the frame to be swung laterally, when desired. This frame is designed to 105 be secured to the thrashing-machine by means of hooks or other suitable means.

Passing horizontally through the upright q is a rod or shaft R, terminating in the diverging arms r and carrying a pulley R', which is 110 connected by a belt i² with a pulley R'' mounted on the main or operating shaft R'''. Extending toward these curved arms r, and at right angles thereto, is another pair of diverging arms t, and located between these 115 arms r and t is a ball S, which is supported from said arms by pins s, thereby furnishing at this point a universal joint. The arms t are formed on the rear extremity of a shaft T, which extends forward a short distance 120 within a tube U. This tube U has a sleeve U' secured to its upper end, and said sleeve terminates in the diverging arms U², the extremities of which are formed with lugs or 125 projections U³, which are received within openings formed in arms U⁴, depending from opposite sides of the frame m. These lugs or projections U³ are perforated and form bearings for a horizontal shaft x, the ends of which pass through said perforations, and they also 130 form pivots or journals on which the frame m and parts carried thereby can be raised or lowered to adjust the angle of inclination. Mounted near one end of this shaft x and car-

ried thereby is a beveled gear-wheel x' , which intermeshes with a beveled gear-wheel h , fixed on the upper extremity of a vertical shaft H , which passes through the sleeve U' into the tube U . On reference to Fig. 2 it will be observed that the tube U is bent at about its center in the arc of a circle, and that within such bent portion is located a coiled spring V , to the opposite ends of which the forward and lowermost ends of the shafts T and H , respectively, are secured, thus forming a flexible shaft.

V' designates a sprocket-wheel, which is mounted on the shaft x and is connected by an endless chain s' (see Fig. 2) with a sprocket-wheel V^2 , fixed on the shaft of the sprocket-wheel C , and a sprocket-wheel V^3 , fixed on the shaft carrying the serrated wheel K .

It will now be seen that motion given to the shaft R will be transmitted by the rod T , spring V , shaft H , and beveled gear-wheels x' and x' to the shaft x , and thence through the sprocket-wheels V' , V^2 , and V^3 and chain s' to the sprocket-wheels C C' and serrated wheel K , thus operating the endless carrier B and said serrated wheel K .

The platform N above referred to is made in sections N' , hinged together, and one of its ends is secured to one leaf of the carrier box A and its other end to the thrasher, as shown in Fig. 6. As above stated, the unbound grain is fed onto this platform, and as the end sections of said platform are folded into a vertical or inclined position they obviously serve as a guide for said unbound grain in its passage from the carrier-box A to the thrasher.

From the foregoing it will be readily seen that perfect movability of my entire device in every direction is secured, the purpose and advantages of which are obvious.

The operation of my device is as follows: The swinging frame and the folding platform having been properly attached to the thrashing-machine and motion given to the operating mechanism described, the bundles are fed to the receiving end of the carrier near the wheel C' . The under side of said receiving end of the carrier is allowed to rest upon the bundles of grain or any other convenient support. As the bundles fall on the endless carrier, they strike on the upwardly-extending prongs of the forks which are constantly and rapidly rising at this point. These prongs take firm hold of the bundles, by reason of the vise-like grasp in which their weighted ends are held, between the bottom of the box A and the lugs or ears o of the endless carrier, thus firmly maintaining, as described, an upright position of said prongs throughout their forward movement and until the bundle comes in contact with and rises upward on the triangular piece M , and the projecting point of the stationary knife L engages with the inside of the band, while the outer side is brought in contact with and engages the teeth of the serrated revolving wheel

K , which, it is proper to here state, may, if desired, be formed with cutting-eyes. The bands are thus severed, and the now unbound grain passes out of the carrier-box at the same time that the forks are released therefrom by the weights of the portions e' thereof or when their points strike the end of the trough F . As the thrashing progresses, the receiving end of the carrier-frame is raised or lowered, or moved from side to side, or the whole device shifted to the opposite side of the thrashing-machine and onto another adjacent mow, stack, or load.

In Fig. 5 I have shown a means whereby the operation of my device may be started and stopped without affecting the operation of the thrasher. This means consists of a lever 3 to be operated by the hand or foot and fulcrumed at 4 to the thrasher. At its rear end this lever is provided with a pulley i and a weight i' , said pulley engaging and taking up the slack of the endless belt i^2 , which is of such length that when not engaged by said pulley i it will not transmit motion from the main or driving pulley R'' to the pulley R' .

I do not wish to be understood as limiting myself to the precise construction herein described, as many modifications will readily suggest themselves to those persons skilled in the art to which this invention appertains. For instance, an inclined serrated knife with a compression wheel or cylinder above it may be substituted for the cutting-knife L , the said serrated knife being pivoted to rise and fall at the proper time, and intermeshing beveled gear-wheels may be located within the tube U as a substitute for the flexible shaft.

Having now described my invention, what I believe to be new, and desire to secure by Letters Patent, is—

1. In a bundle-carrier and band-cutter for thrashing-machines, the laterally-swinging frame and shafts, as T and R , connected by a universal joint, in combination with a vertical shaft, as H , operated by the shaft T and having a bevel gear-wheel at its upper end, a sleeve through which said shaft passes, an endless carrier, sprocket-wheels operating said endless carrier, a horizontal shaft, as x , a bevel gear-wheel thereon intermeshing with the bevel gear-wheel on shaft H , a sprocket-wheel V' , also mounted on said shaft x , a sprocket-wheel V^2 on the shaft of one of the sprocket-wheels operating the endless carrier, and an endless chain connecting said sprocket-wheels V' and V^2 , all substantially as described, and for the purposes set forth.

2. The combination, with the frame and feeding mechanism supported thereby, said frame having depending perforated arms, of means for operating said feeding mechanism and a vertical sleeve through which passes a portion of said operating mechanism, said sleeve having diverging arms formed with lugs received by the perforations in said depending arms and forming a pivoted joint whereby the angle of inclination of the sup-

porting-frame can be changed, substantially as described.

3. In a band-cutter and feeder for thrashing-machines, a laterally-swinging frame designed to be secured to the thrashing-machines, operating-shafts, as T and R, connected together by a universal joint, and a sleeve having diverging arms formed with lugs, in combination with a frame supporting the cutting and feeding devices and arms depending from said frame and having perforations for the reception of the lugs of said diverging arms, all substantially as described, whereby perfect movability of the device in every direction is secured, as set forth.

4. The combination, with the cutting and feeding mechanism of a band-cutter and feeder, of a main shaft, as R, having diverging arms, a shaft, as T, also having diverging arms, and a ball, as S, supported from and between said diverging arms, as described, with means connecting the feeding mechanism with said shaft T, all substantially as described, and for the purposes specified.

5. The combination, in a band-cutter and feeder for thrashing-machines, of a laterally-swinging frame, as Q, designed to be secured to the thrashing-machine, shafts, as T and R, connected together by a universal joint, a frame, as m, pivoted at its rear end, feeding and cutting devices, and means operating said feeding devices from said shaft T, all substantially as described, and for the purposes specified.

6. In a band-cutter and feeder for thrashing-machines, the combination, with a carrier-frame and an endless carrier provided with forks, of sprocket-wheels engaged by said endless carrier and a trough located beneath said frame and having inclined ends in the path of said forks.

7. The combination, with a frame having an opening at one end and a trough beneath said frame in line with said opening, of sprocket-wheels located at opposite ends of said frame, the teeth of one of which sprocket-wheels project through said opening, and a pivoted guard normally covering the portion of said opening not occupied by said sprocket-wheel, substantially as and for the purposes set forth.

8. In a band-cutter and feeder for thrashing-machines, the combination, with the frame, curved leaves hinged to the top thereof, and a trough attached to the under side of said frame, of an endless carrier traveling between said leaves and through said trough, and means for operating said carrier.

9. In a band-cutter and feeder for thrashing-machines, an endless carrier having lugs or ears, forks pivoted on said carrier and having weighted ends, and a band-severing knife, all arranged and combined to operate substantially as and for the purposes set forth.

10. In a band-cutter and feeder for thrashing-machines, an endless carrier having lugs or ears and forks pivoted on said carrier and

having weighted ends, in combination with a band-severing knife and an inclined plane located adjacent to said knife in the path of 70 the bundle.

11. In a band-cutter and feeder for thrashing-machines, the combination, with an endless carrier and forks pivoted thereon and having weighted ends, of a band-severing 75 knife, an inclined plane located in front of said knife, and a toothed or serrated wheel located to the rear of said inclined plane.

12. In a band-cutter and feeder for thrashing-machines, the combination, with the feeding 80 mechanism, of a band-severing knife having a forwardly-projecting cutting-point and an inclined plane in front of said knife.

13. In a band-cutter and feeder for thrashing-machines, the combination, with the feeding 85 mechanism, of a band-severing knife having a forwardly-projecting cutting-point, an inclined plane in front of said knife in the path of the grain, and a serrated wheel at the rear of said inclined plane.

14. In a band-cutter and feeder for thrashing-machines, an endless carrier having lugs or ears, forks pivoted on said carrier and provided with weighted ends, and sprocket-wheels engaged by said carrier, in combination 95 with a band-severing knife having a forwardly-projecting cutting-point, a toothed or serrated wheel located beneath said cutting-point, and an inclined plane located in front of said wheel.

15. The combination, with the frame, endless carrier, and band-severing knife, of semi-cylindrical leaves hinged to the top of said frame and forming when folded a cylinder inclosing said carrier and when open guides 105 for the grain.

16. The combination, with the frame and endless traveling carrier, of a band-severing knife and an inclined plane secured to the top of said frame and semi-cylindrical leaves 110 hinged to the top of said frame and folding together to form a cylinder inclosing said carrier, knife, and inclined plane, and serving when open as a guide for the grain.

17. The combination, in a band-cutter and 115 feeder for thrashing-machines, of the frame, endless carrier, and band-severing knife, with a vertical shaft having a beveled gear-wheel at its top, means for operating said shaft, a horizontal shaft having near one end 120 a beveled gear-wheel intermeshing with that carried by said vertical shaft, a sprocket-wheel near the other end of said shaft, a serrated wheel mounted on a shaft adjacent to said band-severing knife, a sprocket-wheel 125 mounted on the shaft of said serrated wheel, and an endless chain connecting said sprocket-wheel and the sprocket-wheel on the horizontal shaft.

18. The combination, in a band-cutter and 130 feeder for thrashing-machines, of the frame, endless carrier, sprocket-wheels engaged by said endless carrier, and a small sprocket V^2 , mounted on the shaft of one of said larger

sprocket-wheels, with a vertical shaft, means for operating the same, a bevel gear-wheel at the upper extremity of said vertical shaft, a horizontal shaft carrying a bevel gear-wheel intermeshing with that on said vertical shaft, a sprocket-wheel V^2 , also mounted on said horizontal shaft, and an endless chain engaging sprocket-wheels V' and V^2 .

19. The combination, in a band-cutter and feeder for thrashing-machines, of the frame, endless carrier, sprocket-wheels C and C' , engaged by said endless carrier, a sprocket-wheel V^2 , mounted on the shaft of sprocket-wheel C , and band-severing means, with a vertical shaft, means for operating said shaft, a horizontal shaft driven from said vertical shaft and carrying a sprocket-wheel V^2 , a serrated wheel mounted on a shaft adjacent to said band-severing knife, a sprocket-wheel V^3 , mounted beside said serrated wheel, and an endless traveling chain engaging said spur-wheels V' , V^2 , and V^3 .

20. An endless traveling carrier having lugs or ears, in combination with forks pivoted on said carrier and provided with projections engaged by said ears.

21. The combination, with the supporting-frame, of an endless carrier having forks, a band-severing knife, and an inclined plane located adjacent to said knife in the path of the grain.

22. The combination, with the supporting-frame, of an endless carrier having forks, a band-severing knife, an inclined plane located in front of said knife, and a serrated wheel located at the rear of the inclined planes.

23. In combination with means for feeding and severing the bands of grain, an inclined plane located adjacent to the band-severing

devices and a serrated wheel located adjacent to said inclined plane.

24. In a band-cutter and feeder for thrashing-machines, a main frame and band-cutting devices, in combination with an endless carrier passing over the rear edge of said frame, pivoted forks on said endless carrier, said forks having weighted portions, as described, whereby when they reach the rear end of the frame such weighted portions will cause their opposite pronged ends to swing downward prone on the carrier, and means at the forward end of the frame for returning said forks to their original position.

25. The combination, with the operating means of a band-cutter and feeder for thrashing-machines, of mechanism for starting or stopping the operating means of the band-cutter and feeder, the same consisting of a lever provided at its rear end with a weight and a pulley, said pulley operating to take up the slack in an endless belt which loosely connects the drive-pulley on the thrashing-machine with the driven pulley of the operating mechanism of the band-cutter and feeder, substantially as described.

26. The combination, with a thrashing-machine and band-cutter and feeder, of a folding platform secured at one end to the thrasher and at its opposite end to the frame of the band-cutter and feeder, said platform comprising a series of hinged sections, substantially as described.

In testimony that I claim the foregoing I hereunto set my hand this 19th day of July, 75 A. D. 1886.

OZRO S. FELLOWS.
